US00D595664S

(12) **United States Design Patent**
Simard et al.

(10) **Patent No.:** US D595,664 S
(45) **Date of Patent:** ** Jul. 7, 2009

(54) **LIGHTING CONTROL PANEL**

(75) Inventors: **Pierre Simard**, St-Bruno (CA);
Stephane Beland, St-Jean-sur-Richelieu
(CA)

(73) Assignee: **Honeywell International Inc.**,
Morristown, NJ (US)

(**) Term: **14 Years**

(21) Appl. No.: **29/322,117**

(22) Filed: **Jul. 29, 2008**

(51) **LOC (9) Cl.** 13-03

(52) **U.S. Cl.** D13/162

(57) **CLAIM**

The ornamental design for a lighting control panel, as shown and described.

DESCRIPTION

FIG. 1 is a perspective view of a lighting control panel, showing our new design;

FIG. 2 is a front elevation view thereof;

FIG. 3 is a left view thereof;

FIG. 4 is a right view thereof;

FIG. 5 is a top view thereof; and,

FIG. 6 is a bottom view thereof.

The portions illustrated in broken lines on the figures are for illustrative purposes only and form no part of the claimed design.
